CLAIM

The ornamental design for a LED light, as shown and described.

DESCRIPTION

FIG. 1 is a front elevation view of an LED light showing the new design;

FIG. 2 is a back elevation view thereof;

FIG. 3 is a left-side view thereof;

FIG. 4 is a right-side view thereof;

FIG. 5 is a top plan view thereof;

FIG. 6 is a bottom plan view thereof;

FIG. 7 is a perspective view thereof; and,

FIG. 8 is another perspective view thereof.

The equal-length broken lines depict portions of the LED light that form no part of the claimed design.

Areas within the dash-dot broken line boundaries in FIGS. 5, 7, and 8 represent portions of the LED light that form no part of the claimed design.
